[57] CLAIM

The ornamental design for battery charger/analyser design,
as shown and described.

DESCRIPTION

FIG. 1 is a front, left side, isometric view of a battery
charger/analyser design showing our new design;
FIG. 2 is a rear, left side, isometric view thereof;
FIG. 3 is a right side view thereof;
FIG. 4 is a left side view thereof;
FIG. 5 is a front view thereof;
FIG. 6 is a rear view thereof;
FIG. 7 is a top view thereof; and,
FIG. 8 is a bottom view thereof.
